UNITED STATES PATENT OFFICE.

WALTER B. BROWN, OF NEWARK, NEW JERSEY, ASSIGNOR TO THE BIGELOW CARPET COMPANY, OF MASSACHUSETTS.

DESIGN FOR CARPET.

SPECIFICATION forming part of Design No. 27,496, dated August 3, 1897.

Application filed June 23, 1897. Serial No. 641,991. Term of patent 3½ years.

To all whom it may concern:

Be it known that I, WALTER B. BROWN, a subject of the Queen of Great Britain, and a resident of Newark, in the county of Essex and State of New Jersey, have invented a new and original Design for a Carpet and Border, known as Pattern No. 609, of which the following is a specification.

This invention comprises two parts, namely, the design A for a carpet and the design B for a border; and I do hereby declare that the drawing accompanying this specification conveys to any one a clear understanding of the same and is sufficient to enable such person to use my invention.

The body A is characterized by large separated figures of substantially circular outline and smaller ornamental figures between.

The border B is characterized by large sep-

arated figures, similar to those in the body, and a series of festoons of leaf and flower forms.

What I claim as new, and desire to secure by Letters Patent, is—

1. In a design for a carpet, the body A, substantially as shown.
2. In a design for a carpet, the border B, substantially as shown.
3. The design for a carpet comprising the body A and the border B, substantially as shown.

In testimony whereof I have signed my name to this specification in the presence of two subscribing witnesses.

WALTER B. BROWN.
